Fryer, Stiles & Parmer

UNITED STATES PATENT OFFICE.

WILLIAM E. TROUTMAN, OF PITTSBURGH, PENNSYLVANIA, ASSIGNOR TO DUQUESNE STEEL FOUNDRY COMPANY, OF PITTSBURGH, PENNSYLVANIA, A CORPORATION OF PENNSYLVANIA.

ANNEALING BOX.

Application filed August 13, 1926. Serial No. 129,001.

This invention relates to annealing boxes.

In the manufacture and use of annealing boxes, considerable difficulty is encountered in preventing the annealing boxes from distorting or cracking. Boxes of this character, particularly when formed of an integral casting, are extremely difficult to cast in such a manner that the casting will cool in the proper manner without breaking. Annealing boxes are subjected to severe and rapid changes in temperatures, and subjected to unequal temperatures, and for this reason they are extremely liable to become distorted and to crack when they are being used.

10 The present invention proposes to provide an annealing box of an improved construction wherein the walls thereof are of a novel shape, which insures proper support and bracing for the walls in all directions, and 20 which is of such shape as to resist distortion and cracking under extreme temperature conditions.

15 My invention may be readily understood by reference to the accompanying drawings 25 which illustrate a preferred embodiment of my invention and in which—

Figure 1 is a side elevation of an annealing box, part of the box being broken away to show the interior thereof;

30 Figure 2 is a top plan view of the box shown in Figure 1, part of the structure in this view also being broken away to show the interior of the box; and

35 Figure 3 is a section on the staggered line III—III of Figure 2.

The annealing box, which is preferably formed of cast metal and which is preferably an integral structure, has side walls 2, end walls 3 and a top 4. The side walls are preferably formed in such a way as to provide a series of reversely arranged channels which extend from the base of the box vertically up the sides, the channels continuing across the top of the box. The inwardly turned channel portions are designated 5, and the outwardly turned channel portions are designated 6. The channels preferably have substantially perpendicular side walls 7. In each of the interior channels 5 in the side walls 2 of the box are central vertical webs 8. These webs have lateral webs 9 thereon extending transversely thereof which join to the sides of the channel so that the chan-

nels are connected together at intervals along their height by the transverse webs, while the vertical webs 8 impart rigidity to the channel formation. The vertical webs 8 merge at their tops with cross webs 10 that extend down into the inside of the box below the general level of the top thereof.

In each of the external channels 6 in the side walls of the box is a similarly arranged central vertical web 11. This web 11 has lateral webs 12 branching out therefrom at intervals, similar to the webs 9 on the inside 65 of the box, and the webs 12 serve to connect the sides of the external channels and hold them in shape. The webs 12 are preferably staggered with respect to the webs 9, so that they are not in horizontal alignment. 70

The vertical webs 11 preferably terminate below the arched top of the box. Inside the box in line with the vertical webs 11 are cross webs 13 which project down below the general level of the top of the box approximately 75 the same distance that the cross webs 10 project down.

In the inside channels 5 in the top of the box are integral webs 14. The webs 14 are 80 similar to the webs 9, but serve to brace the interior of the top of the box. On the top of the box, in each of the outside channels 6, are one or more bracing webs 15 which serve to tie the sides of the channels in the top of the box together.

85 In each of the end walls 3 there is preferably provided a single internal channel 16 having a vertical bracing web 17 therein. The bracing web 17 has cross webs 18 thereon that tie the sides of the channel together, 90 and the bracing webs 18 are preferably substantially in horizontal alignment with the webs 9.

The channel formation in the side walls of the box gives the box considerable rigidity. The webs arranged in the channels as described brace the structure against warping or cracking in any direction, while the top is strengthened both by the channel formation thereof and by the provision of the webs 10 and 13. The end walls of the box are strengthened by the provision of the channels 16 in the same way that the sides of the box are strengthened.

100 The advantages of the invention arise 105 from the fact that a box is provided which

is securely braced and tied together against collapsing, distortion or cracking in various directions, so that the life of the box is very materially lengthened and the box is more capable of withstanding severe temperature changes and conditions. The reversely arranged channels, in effect, provide non-continuous twin walls for the box. The provision of internal and external webs extending vertically, longitudinally and transversely of the box firmly holds the channels against spreading and give rigidity thereto, and the strength of the box is further increased by staggering the webs so that the box is braced in different horizontal planes inside and out. The arrangement provides, in effect, a wall structure comprised of a plurality of panellike sections staggered with respect to one another and being connected by the transverse walls forming the sides of the channel.

While I have illustrated a preferred embodiment of the invention, it will be understood that this is simply illustrative of the idea of my invention and that various changes and modifications may be made therein, and that the invention may be otherwise embodied within the scope of the following claims.

30 I claim:

1. An annealing box structure having top, side and end walls, the side walls being formed of a plurality of channel portions having substantially flat bottoms and substantially perpendicular sides, some of the channels being turned inwardly and some of the channels being turned outwardly, said inwardly turned channels having bracing webs therein, and said outwardly turned channels having bracing webs therein.

2. An annealing box structure having top, side and end walls, the side walls and top

being in the form of a series of alternately reversed channels, and webs in the channels extending longitudinally and transversely thereof, the transverse webs on the inwardly turned channels being staggered with respect to those in the outwardly turned channels.

3. An annealing box structure having top, side and end walls, the top and side walls being formed of a plurality of continuous channel portions, some of which are turned outwardly and others of which are turned inwardly, webs in the inwardly turned channels extending across the top, and webs in the outwardly turned channels terminating at the top, and webs on the inside of the top in alignment with the webs extending along the outwardly turned channels.

4. An annealing box structure having a top, sides and end walls, the sides being comprised of reversely arranged channel-like portions having substantially perpendicular sides, the widths of the channels being greater than their depths, the said channel portions extending up the sides and continuously across the top of the box, each of the end walls also having a channel therein, all of the channels having perpendicular bracing webs therein, those bracing webs inside the top being of greater height than the depths of the channels.

5. An annealing box structure having a top, sides and end walls, the sides being comprised of a series of panel-like sections arranged in staggered relation to one another, the panel-like sections being connected to each other by transversely extending web portions.

In testimony whereof I have hereunto set my hand.

WILLIAM E. TROUTMAN.
